UNITED STATES PATENT OFFICE.

DAVID L. HOUGH, OF NEW YORK, N. Y., ASSIGNOR TO THE UNITED ENGINEERING AND CONTRACTING COMPANY, OF NEW YORK, N. Y., A CORPORATION OF NEW YORK.

TUNNEL CONSTRUCTION.

SPECIFICATION forming part of Letters Patent No. 727,799, dated May 12, 1903.

Application filed February 7, 1903. Serial No. 142,288. (No model.)

To all whom it may concern:

Be it known that I, DAVID L. HOUGH, a citizen of the United States, residing in the borough of Manhattan, city of New York, in the 5 State of New York, have invented certain new and useful Improvements in Tunnel Construction, of which the following is a specification, reference being had to the accompanying drawings, forming a part hereof.

10 In the construction of tunnels by the shield method, in which the placing of the lining goes on with the advance of the shield, much difficulty is usually experienced in maintaining a reasonably-tight joint between the 15 shield and the tunnel-lining for the effectual exclusion of water.

It is the object of this invention to provide simple and effective means for making the joint between the lining and the shield tight 20 enough to exclude water without interfering with the advance of the shield or with the placing of successive sections of the lining.

In accordance with the invention a U-shaped packing - ring is provided, with its 25 members lying against the shield and lining, respectively, and its open mouth toward the rear, so that it shall be pressed against the lining and shield by the pressure from without, means being provided for holding the 30 ring in place and for moving it forward from time to time as required.

The invention will be more fully described hereinafter with reference to the accompanying drawings, in which—

35 Figure 1 is a view in longitudinal section, showing portion of a shield and tunnel lining with the packing interposed; and Fig. 2 is a view, partly in transverse section on the plane indicated by the line 2 2 of Fig. 1 and 40 partly in elevation.

In the embodiment of the invention shown in the drawings the tunnel-shield, which may be of any preferred form and construction, is represented at *a*, and the successive sections 45 of tunnel-lining, which also may be of any

preferred form and construction, are represented at *b*. The packing *c*, which is of a suitable fabric or other sheet material, is folded in U shape with its opposing members or sides lying against the interior of the shield 50 and the exterior of the lining, respectively, and with the open mouth toward the rear, so that the fluid-pressure upon the exterior of the tunnel-lining itself serves to maintain close contact between the members or sides 55 of the packing-ring and the shield and lining. A rod *d*, bent to conform to the curvature of the tunnel-lining and made in sections, if desired, is placed within the packing at its forward edge and serves to hold the packing in 60 shape and in place. Bolts *e* may be secured to the ring or rod *d* through the packing, both to secure the ring or rod to the packing and to provide means by which the packing may be held in any position and advanced from 65 time to time, as may be required. The packing is preferably prepared exteriorly, as by dressing with black-lead or other suitable material, so that it may be moved along as required without excessive friction and without 70 requiring additional means or devices for reducing the external fluid-pressure upon the sides or the opposing members of the packing.

I claim as my invention—

1. The combination with a tunnel - shield 75 and a tunnel-lining, of a packing interposed between the shield and lining, and having its opposing members lying against the shield and lining to be held by external fluid-pressure.

2. The combination with a tunnel - shield and a tunnel-lining of a U-shaped sheet-packing interposed between the shield and lining and having its opposing members lying against the shield and lining respectively to 85 be held by external fluid-pressure.

3. The combination with a tunnel - shield and a tunnel-lining, of sheet-packing interposed between the shield and lining, and having its opposing members held against the 90

shield and lining respectively by external fluid-pressure, and means to hold the packing in place and shape.

4. The combination with a tunnel-shield 5 and a tunnel-lining, of a packing interposed between the shield and lining, and having its opposing members held against the shield and lining respectively by external fluid-pressure, and a rod having a curvature to conform with

the tunnel-lining and engaging the packing to at its forward edge to hold the packing in place and shape.

This specification signed and witnessed this 5th day of February, A. D. 1903.

DAVID L. HOUGH.

In presence of—

J. H. DUNSTAN, Jr.,
FREDK. A. GUENTHER.
